UNITED STATES PATENT OFFICE.

WASHINGTON CLAYPOOLE, OF PHILADELPHIA, PENNSYLVANIA.

UNLOADING APPARATUS.

No. 889,906.

Specification of Letters Patent.

Patented June 9, 1908.

Application filed July 31, 1907. Serial No. 386,429.

To all whom it may concern:

Be it known that I, WASHINGTON CLAY-
POOLE, citizen of the United States, residing
at Philadelphia, in the county of Philadel-
5 phia and State of Pennsylvania, have in-
vented new and useful Improvements in Un-
loading Apparatus, of which the following is
a specification.

My present invention pertains to appara-
10 tuses for unloading substances, particularly
coal, from wagons and other vehicles; and it
contemplates the provision of an efficient appa-
ratus through which coal may be conveyed
15 from the end of a vehicle body and dis-
charged laterally in one direction or the
other to a sidewalk or the like.

The invention also contemplates the pro-
vision of an apparatus for the purpose stated,
adapted when not in use to be conveniently
20 fastened close to the end of the vehicle body
so as not to form a considerable projection at
such end.

Other objects and advantages of the in-
vention will be fully understood from the
25 following description and claims when the
same are read in connection with the draw-
ings accompanying and forming part of this
specification, in which:

Figure 1 is a perspective view illustrating
30 the apparatus constituting the preferred em-
bodiment of my invention as properly ar-
ranged relative to a wagon body to convey
coal or other substance from the rear end of
35 the body and discharge the same to a point
at the left hand side of the body. Fig. 2 is a
rear elevation showing the apparatus as se-
cured in idle position against the end wall of
40 the wagon body. Fig. 3 is a horizontal sec-
tion taken in the plane indicated by the line
3—3 of Fig. 1, looking downward, but show-
ing the chute of the apparatus as reversed—
i. e., positioned to discharge the coal at the
45 right hand side of the wagon body. Fig. 4 is
a longitudinal vertical section taken in the
plane indicated by the line 4—4 of Fig. 3.

Similar letters designate corresponding
parts in all of the views of the drawings, re-
ferring to which: A is a wagon body having
at its rear end a discharge a. This discharge
50 a is preferably in the form of an opening
formed in the rear end wall b of the body;
and it is by preference designed to be closed

by a vertically slidable door c, best shown in
Figs. 3 and 4.

B is the spout of my novel apparatus. C 55
is the transverse chute thereof.

D is a spring catch connected to the bot-
tom of the body A and designed to coöperate
with a lug E on the spout B in order to re-
tain the spout in the working position shown 60
in Figs. 1, 3 and 4, and F is a cable, prefer-
ably in the form of a chain, connected to the
wall b of the body at a point above the open-
ing a and having for its office to retain the
spout B and chute C in the idle position 65
shown in Fig. 2.

The spout B is preferably formed of sheet-
metal shaped as illustrated, and its side walls
are connected to a rod G, journaled in bear-
ings H carried by the end wall b at the oppo- 70
site ends of the opening a. Adjacent to its
outer end the said spout B is provided with a
cross-bar d for the connection of the chute C,
and at its inner end the bottom of the spout
is provided with a lip e which, when the 75
spout is in working position, is designed to
rest on the bottom wall of the opening a after
the manner shown in Figs. 1 and 4. The
chute C is also formed of sheet-metal, and its
shape in cross-section is definitely illustrated 80
in Fig. 4. It is open at one side throughout
its length and is provided across said opening
at a point above its discharge end with a
cross-bar f to which is connected one end of a
longitudinal central rod I, the opposite end 85
of which is secured in the main portion of the
chute, as indicated by g in Fig. 3. Between
the said rod I of the chute C and the cross-
bar d of the spout B is interposed a loose con-
nection J which, as best shown in Fig. 4, is 90
made up of an eye h swiveled to the bar d, a
link i connected to the rod I, and a link j con-
necting the said eye h and link i.

When the chute C is in the position shown
in Fig. 1, relative to the spout B, one wall of
the opening in the chute bears against the
underside of the spout. Then when it is de-
sired to reverse the chute—i. e., adjust it to
the position shown in Fig. 3, it is simply nec-
essary to first swing the chute rearward to 100
enable it to clear the rear end of the spout B,
then swing the chute transversely of the
wagon toward the right, and then permit the
chute to swing forward until the opposite

wall of the opening in the chute bears against the underside of the spout. To adjust the chute from the position shown in Fig. 3 to that shown in Fig. 1, the operation described 5 is simply reversed.

In the practical use of my improvements, the opening *a* is closed through the medium of the door *c* while the loaded wagon is *en route* to its destination, and the spout *B* and chute *C* are fastened close against the end wall *b* of the wagon body *A* through the cable *F* which from its point of connection to the said body is passed downward in rear of the chute *C* and spout *B* and under the catch *D*, 10 and is then suitably secured, preferably by engaging the hook *k* provided at its free end with the rod *G* in the manner clearly illustrated in Fig. 2. When the wagon arrives at its destination the hook *k* is disengaged from 15 the rod *G*, and the spout *B* with the chute *C* thereon is swung downward until the lip *e* of the spout brings up on the bottom wall of the opening *a*, and the lug *E* of the spout is engaged with the catch *D* of the body *A*. 20 25 When the spout *B* is thus secured against casual movement, and the door *c* is raised above opening *a*, as shown in Fig. 4, it will be seen that coal may be readily shoveled from the interior of the body *A* into the spout *B*; 30 and it will also be seen that the said coal will pass from the spout *B* to the chute *C*, and will be conveyed by the latter in a direction transverse with respect to the body *A* and discharged at a point at one side of the said 35 body. When the chute *C* is arranged as shown in Fig. 1, the coal will be discharged at the left hand side of the body *A*, but when the said chute is reversed and arranged in the position shown in Fig. 3, the coal will be 40 discharged at the right hand side of the body *A*. Thus it will be seen that irrespective of the direction in which the wagon moves alongside the curb of a sidewalk, my novel apparatus may be made to discharge the coal laterally upon the sidewalk. 45

Subsequent to the unloading of the wagon body *A* in the manner described, the spout *B* and the chute *C* are swung upward to the position shown in Fig. 2 and are secured in 50 such position through the medium of the cable *F*, after which the door *c* is moved downward to close the opening *a* and adapt the body to receive another load. With the spout *B* and chute *C* secured in the idle position stated it will be readily appreciated that 55 said spout and chute offer but a slight projection at the rear end of the body *A* as is desirable.

The construction herein shown and 60 described constitutes the preferred embodiment of my invention, but it is obvious that in practice such changes or modifications may be made as fairly fall within the scope of my invention as defined in the claims appended.

Having described my invention, what I claim and desire to secure by Letters-Patent, is:

1. An unloading apparatus for wagons and other vehicles, comprising a spout, and a chute disposed at a right angle to the spout and having an opening in its top and also having the side walls of said opening arranged, in different positions of the chute, to bear against the underside of the spout; the said chute 75 being loosely connected with the spout and being arranged, when moved out of engagement with the spout, to be swung vertically from one position to a reverse position.

2. An unloading apparatus for wagons and 80 other vehicles, comprising a spout having a cross-bar adjacent to its outer end, and a chute disposed at a right angle to the spout and having an opening in its top, a cross-bar and a longitudinal rod connected to its main 85 portion and said cross-bar and also having the side walls of its said opening arranged, in different positions of the chute to bear against the underside of the spout; the longitudinal rod of the chute being loosely connected with the cross-bar of the spout and the chute being arranged, when moved out of engagement with the spout, to be swung vertically from one position to a reverse position.

3. The combination of a vehicle body having a discharge opening, a vertically swinging spout hinged to said body and arranged in one position to receive from said discharge opening, a chute connected and movable with the spout and arranged to receive therefrom and also arranged to discharge laterally relative to the spout, and means for removably securing the spout and chute against the body when the same are swung upward. 100

4. The combination of a vehicle body having a discharge opening, a vertically swinging spout hinged to said body and arranged in one position to receive from said discharge opening and having a lug on its under side, a resilient catch carried by the body and arranged when the spout is in its lower position to engage the lug thereof, a chute connected and movable with the spout and arranged to receive therefrom and also arranged to discharge laterally relative to the spout, and a cable connected to the body and arranged to be passed over the chute and the spout and under the catch and having means at its free end whereby it may be connected 110 detachably with the body.

5. The combination of a vehicle body having a discharge opening, a vertically swinging spout having a rod journaled in bearings on the body and also having a cross-bar adjacent to its outer end; said spout being arranged in one position to receive from said discharge opening and being provided with a lug on its under side, a resilient catch carried by the body and arranged when the 125 130

spout is in its lower position to engage the lug thereof, a chute arranged to receive from the spout and also arranged to discharge laterally relative thereto and having a cross-
5 bar and a rod connected to said cross-bar and its main portion, a connection between the cross-bar of the spout and the rod of the chute comprising a member swiveled in the cross-bar, and a cable connected to the body
10 and arranged to be passed down over the

chute and the spout and under the catch and having a hook at its free end for the purpose set forth.

In testimony whereof I have hereunto set my hand in presence of two subscribing wit- 15
nesses.

WASHINGTON CLAYPOOLE.
